Walter Scott Morton,
INVENTOR BY
Charles N. Woodward, Atty.

UNITED STATES PATENT OFFICE.

WALTER SCOTT MORTON, OF ST. PAUL, MINNESOTA.

ELEVATOR-HATCHWAY GUARD.

SPECIFICATION forming part of Letters Patent No. 317,564, dated May 12, 1885.

Application filed February 9, 1885. (No model.)

To all whom it may concern:

Be it known that I, WALTER SCOTT MORTON, a citizen of the United States, and a resident of St. Paul, in the county of Ramsey, 5 in the State of Minnesota, have invented certain new and useful Improvements in Elevator-Hatchway Guards, of which the following is a specification.

Figure 1 is a sectional side view, Fig. 2 is 10 a sectional front view, and Fig. 3 is a sectional plan view, of a portion of an elevator, showing the manner of attaching my improvement to the hatchways. Fig. 4 represents a detail of the angular lever, showing its position 15 when the guard or door is elevated. Fig. 5 is a partial front view similar to Fig 2, showing the guard partially raised.

This invention relates to hoisting-elevators, and more especially to that class used in manufacturing and mercantile buildings for transferring goods from floor to floor; and it consists 20 in a gate, door, or bar adapted to be automatically raised and lowered across the entrance of the hatchways by the elevator-platform when running up and down.

A² is one of the floors of a building having a hatchway, B².

C² C² are the guide-timbers between which the platform or cage runs up and down. This 30 cage or platform usually consists of a floor, D², side pieces or uprights, D² D³, and top cross-piece, D⁴, to the latter of which the hoisting-cable D⁵ is connected.

The hatchways are left open, and the only 35 guard required is a gate or bar dropped across the entrance. These gates or bars are hinged at one end and raised by the other end.

The gate or guard consists in a bar, E', pivoted in an upright post, E², at one corner 40 of the hatchway B², and adapted to rest by its other end in a notch or open slot in the top of another post, E³, attached at the opposite corner of the hatchway, as shown. An angular lever is pivoted at a' to a bracket or hanger, a², on one of the guides, C or C², or to some other fixed part of the building, this lever having a short upwardly and backwardly trending arm, F', and a longer substantially horizontal arm, F², as shown. One 45 of these levers F' F² will be attached to the elevator at each floor; but as they all operate 50

precisely alike a description of one will be sufficient. The short arm F' has a small friction-roller, b, in its outer end in close proximity to one of the uprights, D² or D³, the latter having a trip-plate, D⁶, attached to it, as shown. To the outer end of the long arm F² one end of a cord or small wire cable, d', is attached, and which then passes upward over a pulley, d², and thence downward and is 60 attached to one end of a lever, G'. The other end of the lever G' is pivoted at e to the bar E', lying, when the bar E' is horizontal, at about an angle of forty-five degrees, as shown in Fig. 2. The lower end of this lever G', 65 near the cord d', is provided with a friction-pulley, h, adapted to run up and down in contact with the post E², as hereinafter shown.

E⁴ are small bars, pivoted at regular intervals by their upper ends in the bar E', and each pivoted by its lower end in another bar, E⁵, parallel with the bar E', as shown. By this means, when the bar E' is resting in its horizontal position, as shown in Fig. 2, the bars E⁴ will hang down perpendicularly, and the bar E⁵ will lie horizontally 75 and parallel with the bar E', the whole forming a gate across the entrance to the hatchway.

When the gate is in the position shown in 80 Fig. 2, the levers F' F² and G' will be in the position shown in Figs. 1 and 2. Then, when the elevator-platform is lowered or elevated, the inclined ends i' or i² of the trip-plate D⁶ striking the friction-roller b in the end of the 85 short arm F' of the trip-lever will raise it upward and depress the longer end, as shown in Fig. 4. The cord d' will thus draw the lower end of the lever G' (when the latter is used) upward along the post E² and elevate the bar 90 E', as shown in Fig. 5. The gate is shown only partially elevated in Fig. 5 to render the drawing more clear and distinct; but as a matter of course it will be readily understood that the bar E' will be turned up to a substantially perpendicular position, the bars E⁴ and E⁵ folding up against the bar E', and thus leaving the entrance to the hatchway entirely 95 unobstructed.

The trip-plate D⁶ will be so placed with reference to the lever F' F² and the latter so arranged relative to the gate that the gate will 100

be elevated to its perpendicular position when the floor D' of the cage is even with the floor A of the building, the same rule also, of course, applying to the door N.

- 5 If the elevator-platform is running downward, then the lower inclined end, i², of the trip-plate D⁶ will first strike the lever F' and elevate the gate, the gate being held elevated while the straight or curved part of the trip-plate between the inclines i' i² is in contact with the lever. If, on the other hand, the platform is running upward, then the upper incline, i', of the trip-plate will first strike the lever; but the action on the levers and gate 10 will be the same in both cases. When the platform begins to run up or down again, or when passing through a hatchway where it does not stop, then the gate is simply opened and closed again as the platform passes 15 through the incline i' or i² which is last in contact with the lever F' F², serving to "check" the downward motion of the gate and prevent its falling too suddenly of its own weight.
- 20 Under some circumstances it might be found advantageous to reverse the lever F' F² and cause its long end to pull upward upon the lever G' or the bar E', in which case the pulley d² might be dispensed with.
- 25 The long arm of the lever need not necessarily be arranged so as to assume a substantially horizontal position, as above mentioned, but may be arranged in any suitable manner, so that the outer end of the long arm moves 30 through a sufficient space to operate the gate or door.

When used in connection with elevators arranged to receive and discharge freight from two sides, then two sets of gates, doors,

and their tripping mechanisms may be used, 40 or by a few additional pulleys and a longer cord two or more gates may be operated by one set of trips and levers.

Having thus described my invention, what I claim as new is—

1. An elevator-platform and a doubly-inclined trip-plate attached thereto, in combination with a gate-bar pivoted at one end to a suitable frame-work, a lever pivoted at one end to said gate-bar, a friction-pulley on the free 50 end of said lever which travels on a fixed vertical guide or way, an angular lever pivoted at its angle to a fixed frame, one arm of which lever engages with said trip-plate, and a cord which connects the other arm of said lever 55 with the lever which is pivoted to the gate-bar, substantially as set forth.

2. An elevator-platform and a doubly-inclined trip-plate, D⁶, attached thereto, in combination with an upright post, E², a gate-bar, 60 E', pivoted thereto, a lever, G', pivoted at its upper end to said gate-bar and provided at its lower end with a friction-pulley, h, which is adapted to travel vertically on said post E², an angular lever having arms F' F², pivoted at its angle to a fixed part, one arm of which engages with said trip-plate, friction-pulley d², and a cord passing over said pulley 65 which connects the other arm of said angular lever with said lever G', substantially as set 70 forth.

In testimony whereof I have hereunto set my hand in the presence of two subscribing witnesses.

WALTER SCOTT MORTON.
